CLAIM

The ornamental design for a ski goggle nose and face guard, as shown and described.

DESCRIPTION

FIG. 1 is a rear elevational view of a ski goggle nose and face guard showing my new design, the goggle being shown in broken lines for illustrative purposes only;

FIG. 2 is a front elevational view thereof on an enlarged scale;

FIG. 3 is a side elevational view thereof on an enlarged scale;

FIG. 4 is a top plan view thereof on an enlarged scale;

FIG. 5 is a bottom plan view thereof on an enlarged scale.

*Fig. 1.**Fig. 4.**Fig. 2.**Fig. 3.**Fig. 5.*
